UNITED STATES PATENT OFFICE.

LE GRAND PARISH, OF MOUNTAIN VIEW, NEW JERSEY, ASSIGNEE TO AMERICAN ARCH COMPANY, OF NEW YORK, N. Y., A CORPORATION OF DELAWARE.

LOCOMOTIVE-FIRE-BOX STRUCTURE.

Application filed June 4, 1919. Serial No. 301,786.

To all whom it may concern:

Be it known that I, LE GRAND PARISH, a citizen of the United States, residing at Mountain View, in the county of Passaic and State of New Jersey, have invented certain new and useful Improvements in Locomotive-Fire-Box Structures, of which the following is a specification.

This invention relates to locomotive fire box structures and particularly to an improved arrangement of circulation of arch tubes therefor.

One of the primary objects of my invention resides in the provision of an improved structure whereby the circulation, and consequently the efficiency of the boiler, are greatly increased, while at the same time accessibility to the flues and staybolts for purposes of repair or inspection is retained. Another object of the invention resides in the provision of an improved construction of the character specified in which the ends of the tubes themselves are readily accessible and by which the improvement is made readily applicable to locomotive fire boxes of the shallow type.

My invention also contemplates an improved arrangement of the character specified which does not detract from the flexibility of the boiler structure for contraction and expansion, and by means of which various forms of refractory arches may be employed which are adapted to thoroughly intermix the gases, thus promoting combustion.

The foregoing together with such other objects as may hereinafter appear, or are incident to my invention, I obtain by means of a construction which I have illustrated in preferred form in the accompanying drawings wherein:

Figure 1 is a longitudinal section through a locomotive fire box embodying my improved features; Figure 2 is a cross section through the fire box of Fig. 1, showing the arches in end elevation; Figure 3 is a cross section taken on the line 3—3 of Figure 1; and Figure 4 is a section taken on the line 4—4 of Figure 1.

Referring now particularly to Figures 1 and 2, the fire box comprises the inside and outside throat sheets 7 and 8; inside and outside side sheets 9 and 10; inside and outside back sheets 11 and 12; a crown sheet 13; a top sheet 14; and a flue sheet 15; the

arrangement providing the usual water walls closed by the mud ring 16.

In carrying out my invention I provide a row A of circulation tubes 17, four in number, which extend rearwardly and upwardly preferably connecting the front water leg with the rear water leg, the tubes being expanded in the throat sheet 7 and the inside back sheet 11, and preferably having a bend intermediate their ends. Above the row A of circulation tubes, I provide a second row B having the same number of tubes extending in substantially the same vertical planes as the tubes of the first row and connecting front and rear water legs. At the front ends, the tubes of the row B are connected to the inside throat sheet 7 in approximately the same plane as the tubes of the lower row, this being accomplished by bending the ends of the upper tubes laterally and downwardly, as indicated at 18. The rear ends of the outer pair of tubes of the upper row are also bent inwardly to permit of connecting the same to the inside back sheet.

It will be seen that the increase in the number of tubes will increase the circulation through the boiler, while at the same time the flexibility of the fire box structure for expansion and contraction is not impaired, the tubes are readily accessible for cleaning, the arrangement can be applied to shallow fire boxes, allowing use of a double arch in such structures without bringing the tubes too low at the front of the box and ready access can be had to the flues.

Furthermore, the arrangement is such that it accommodates itself to support various forms of arches adapted to secure intimate admixture of the gases. In the exemplification shown in the drawings there is an arch C, comprised of three rows of arch bricks 20 supported on the upper row of tubes; and two side arches, each consisting of a row of wing bricks 21 supported from side sheets and an outer tube of the lower row, and of a row of bricks 22 each supported on an outer pair of tubes of such lower row. This arrangement of the arches leaves open space, as result of which the gases will follow a more or less tortuous path in which they are thoroughly intermingled. The two rows A and B of circulation tubes are spaced sufficiently far apart to permit of the ready introduction of the arch bricks for initial installation or for repair.

In order to support the arch bricks from the inside throat sheet 7, I provide special bricks D (see Figs. 1, 2 and 4). In the bottom face of such bricks, I provide a 5 socket or groove 23 adapted to fit the circulation tubes of the lower row; and the bricks are tapered from the front to the rear, there being provided at the rear upper portion thereof a notch 24 adapted to receive the ends of the bricks of the forward course of the arch C. In order to accommodate the special bricks D to the type of reversible arch bricks shown in the drawings, I may provide an upstanding rib 25 curved 10 to fit the socket portions of the arch bricks (see Fig. 4). The bricks are also cut away on one side, as indicated at 26 in Figure 4, so that the bricks may be inserted between the two rows of tubes. As a result of the 15 peculiar configuration of the bricks, they are locked between the rows of tubes as against vertical displacement and lateral displacement in one direction, the wedging action of the arch bricks serving to lock the 20 bricks against lateral displacement in the opposite direction. The weight of the arches serves to hold the bricks D securely against the throat sheet, in which connection it is to be noted that the forward bricks 25 22 of the side arches bear against the rear face of the bricks D (see Fig. 1).

I claim:

1. A boiler fire box construction comprising in combination, a forward water leg, a 35 rear water leg, a plurality of arch tubes connecting said legs, said tubes being arranged in two rows with the tubes of one row located respectively in substantially the same vertical planes as the tubes of the other row, 40 said tubes being connected to a sheet of the forward water leg in substantially the same horizontal plane, and baffling bricks supported on the tubes, the bricks on the upper

tubes being arranged to present a solid central arch with spaces at the sides and the 45 bricks on the lower tubes being arranged to present solid side arches with a space therebetween and beneath the solid central arch.

2. A boiler fire box construction comprising in combination, water spaces, eight arch tubes connecting said water spaces, said tubes being arranged in two rows with the tubes of one row located respectively in substantially the same vertical planes as the tubes of the other row, said tubes being connected to a sheet of a water space in substantially the same horizontal plane, a plurality 50 of baffle bricks on the upper tubes forming an arch with spaces between said arch and the sides of the fire box, a plurality of bricks 55 spanning the space between the sides of the fire box and the outer tubes of the lower row, and a plurality of bricks spanning the spaces between each outer tube and the next adjacent tube of the lower row.

3. A locomotive boiler fire box construction comprising in combination, a front water leg, a rear water leg, eight arch tubes connecting said water legs and arranged in pairs with the tubes of each pair located 70 one above the other in a substantially vertical plane, said tubes being connected to a sheet of the forward water leg in substantially the same horizontal plane, a plurality 75 of bricks forming an arch on the upper tubes with spaces between said arch and the sides of the fire box, a plurality of bricks spanning the spaces between the sides of the box and the outer lower tubes, and a plurality 80 of bricks spanning the spaces between each outside tube of the lower row and the tube adjacent thereto.

In testimony whereof, I have hereunto signed my name.

LE GRAND PARISH.
